UNITED STATES PATENT OFFICE.

EDWIN GEBHARDT, OF NORWOOD, OHIO.

DETACHABLE BUTTON.

1,268,833.

Specification of Letters Patent. Patented June 11, 1918.

Application filed March 27, 1916. Serial No. 86,839.

To all whom it may concern:

Be it known that I, EDWIN GEBHARDT, a citizen of the United States, and a resident of the city of Norwood, in the county of 5 Hamilton and State of Ohio, have invented certain new and useful Improvements in Detachable Buttons, of which the following is a full, clear, and exact description, reference being made to the accompanying drawing, forming part of this specification.

My invention relates to detachable buttons having means for automatically securing them in place in a buttonhole or the like. Such buttons are used principally for insignia to be attached to the coat lapel or the like, but they may also be used for any purpose in which a button is applied, such as a shirt stud, a fancy vest button and such like. I have as my object the providing of a button which may be easily attached in place, and which cannot be dislodged by a straight pull, but may be removed easily and quickly by merely separating the parts thereof with a screwing motion.

25 I have discovered that by providing a certain friction holding device in a button back, that a button having a post may be inserted in the friction device and cannot be removed therefrom. However the twisting and pulling 30 of the parts at the same time will separate them, and accordingly it is my object to provide a button having these features.

It is old in the art to provide a button which may be attached in place and removed 35 by separating the parts, but the disadvantage of structures of this nature has been that it is a tedious matter to insert the buttons in cards for sale. A button in which the post screws into the back, for example, 40 requires a screwing into the mounting or display cards for each individual button. The labor is very difficult, as the buttons are so small and the time of mounting an order of say, one hundred thousand campaign 45 buttons, would be prohibitive. Then, too, this labor of inserting the button is disagreeable to the user as well. A button in which the post merely pushes into place in a backing portion is not satisfactory for the purpose 50 of my button unless it is removable, so the various devices in the class of buttons known as "bachelors' buttons" do not answer for my purposes. In these buttons the post pushes into place, but once there it is

not removable unless the button is broken to 55 pieces.

The objects of my invention, whereby the above difficulties are done away with, I accomplish by that certain construction and arrangement of parts to be hereinafter more 60 specifically pointed out and claimed.

In the drawing,

Figure 1 is a perspective view of a button assembled.

Fig. 2 is a like view of the back portion 65 of the button.

Fig. 3 is a vertical sectional view of the revolving disk mounting.

Fig. 4 is a perspective view of the retaining disk.

70 Fig. 5 is a vertical section of a modified form of the parts shown in Fig. 2.

Fig. 6 is an elevational view showing the retaining disk in place over a button post.

Fig. 7 is a perspective view of another 75 form of button disk.

The button has a head 1, which has on it the decoration of the button. Thus if it is a vest button, it will have some sort of jewel mount or the like, and if it is an insignia 80 button it will be faced with an emblem, or device such as may be desired. This head has a post 2 extending therefrom, which post may be smooth or screwthreaded. The smooth post is practical, as it is all that is 85 necessary and will hold perfectly, as well as unscrew, as will be described; but since it is desired to have a post which is easier to unscrew, the screw post is preferred.

90 The essential feature of the back or retaining portion of the button is an expanding, retaining disk, securely held in a shell of any desired type. The disk might, if desired, in a very cheap construction, be used by itself, but the separation of the parts would not be 95 so easy as will be noted. The disk 3 is constructed preferably of steel, and has a central aperture 4 of approximately the size of the button post. From this aperture are cut the radial cuts 5, 5, to give the disk the 100 expanding feature, and further cutaway portions 6, 6, may be made as desired to give spring and resiliency to the disk. The periphery of the disk has preferably the cuts 7, 7, therein to facilitate the tight holding 105 of the same within the shell 8 of the back, and add further resiliency.

In the preferred form of disk, Fig. 4, the

slits 5 are very short and the cutaway portions 6 abut the central aperture, so as to leave the cut edges of the hole 4 in the shape of points *a*, *b*, *c*, *d*. In this form also the 5 cuts at 7 are made so as to leave flattened edges 7^a, 7^b, which serve the same purpose as the cuts 7 (Fig. 7), and economize in cost of production, at the same time strengthening the disk. The added resiliency of the 10 alternative form (Fig. 7) is not needed in the form of disk shown in Fig. 4.

The operation of the disk is not dependent upon the way it is mounted. The post of the button is inserted in the disk and 15 pushed in. This will result in a spreading of the metal around the aperture by the thicker portions of the post, and these portions will remain in spread position, firmly 20 clamping the disk on the post. A pull on the disk or post will not separate them, but will pull them more tightly together, but it is comparatively easy to unscrew the disk 25 from the post. The disk and post are the essential features of my invention, and the other parts are merely intended to make simple and easy the operation of the parts, and for the sake of neatness of appearance.

It is not necessary to have a tapered post for the button, and the post in Fig. 6 is the 30 desired form. The size of the aperture 4 in the retaining disk is to be smaller than the post, but its sizing does not need to be accurate, and it will fit considerable variations of posts.

35 This feature is a great advantage in button making, as the parts are small and variations in size of posts in any one lot of buttons are bound to occur. In the past, if the screw post, for example, were not the right size, the button would have to be rejected.

The back of the button in the most convenient form comprises a shell 8, having in most types of button a central rear aperture 45 9 to allow passage of the post 2 when it is inserted. This shell is brought up around the disk and holds it tightly and nonrotatably in place. A disk 10 is provided, on which is pivoted a rotating smaller disk 11. The edges 12 of the shell are bent over the 50 edge of the disk 10 and this disk forms the closure for the backing piece. The rotatable or pivotal mounting of the disk 11 comprises a tubular portion 13, secured on the inside 55 of the disk 10, and extending through the disk 11, being bent over at 13^a to loosely engage said disk 11. This disk 11 has teeth 14 on its outer surface, for a purpose to be described, and the tubular member serves as 60 the entering aperture for the button post.

If preferred, the disk 10 may be provided with teeth 14, and the rotatable member entirely omitted (Fig. 5), thus simplifying the parts, but making it a little more difficult to 65 separate the post from the retaining disk.

For that matter, the teeth might be omitted entirely, but this would render the backing without any function except for appearance, as there would be about as much difficulty in separating the parts of the button as if the 70 backing were omitted altogether.

The operation of the button is very simple. For affixing the post in place, where it will be locked as described, it is merely pushed into the hole in the backing. When this is 75 done, the teeth 14 will engage in the rear of the cloth in which the button is placed. In removing the post from the back, it must be unscrewed. In the modification in Fig. 5, the head of the button is taken in the fingers and unscrewed in the ordinary manner, the teeth holding the back of the button in the cloth.

In the form shown in Fig. 2, the back and button may be unscrewed together, one from 85 one side and one from the other of the cloth, as the toothed disk will hold fast to the garment.

If the teeth are absent altogether, the button will not stay in place so well, and for 90 this reason among others I prefer to have the backing toothed as shown. The parts may be unscrewed, however, as is obvious.

In order to provide for a disk that will unscrew easily from a screw post, and that 95 will not strip the threads in unscrewing, the following devices are employed: In the first place the screwthreads 15 on the post 2 are made with flat faces so that pushing the post into the back will not tend to rub away the 100 thread.

The disk is formed with its points *a*, *b*, on one side of the disk, and *c*, *d*, on the other, alternately turned up and down. Thus the points *a* and *d*, and the points *b* 105 and *c* will fit within the threads on opposite sides of a screw post within certain limits to allow for variation.

If these points were not turned up and down, or if the slit portions of the disk were 110 allowed to remain as in Fig. 7, then the unscrewing of the disk would result in a stripping of the threads of the post. This is because a disk having an aperture the approximate size for the screw would be of less 115 cross-sectional area than the horizontal cross-section of the screw. The points being turned up and down, however, allow the disk to unscrew horizontally, without being forced over the top of a thread at every revolution. 120

It has been found that a disk constructed as above described will push on and unscrew from a button post for years of ordinary use without stripping the thread.

It should not be construed that this 125 invention is only applicable to the type of button known as the insignia button. The feature of a separable button which can be securely fastened into place by pressing its parts together and which has no special de- 130

vice for releasing the post from the back, is as applicable to shirt studs and buttons as well as lapel buttons.

I do not wish to be limited in the claims that follow to the exact structure described in the foregoing specification as the description refers but to the preferred form of my invention; on the contrary I wish to be entitled to the full scope of the doctrine of equivalents in the construction of my claims. Also I do not wish to be limited in my claims because of my failure at this time to appreciate the full usefulness of my invention, as I intend it to be used in the future in any manner that may turn out to be economical and convenient, and that mere mechanical changes necessary to adapt it to future uses be fully included in the scope of my invention.

Having thus described my invention, what I claim as new and desire to secure by Letters Patent, is:

1. In a removable button, a flat disk having a central aperture, with the body of the disk slit adjacent the aperture to form spring tongues, a back for the button bent around the said disk and having an aperture registering with the aperture in the disk, said disk having its edges cut at the periphery thereof to prevent the rotation thereof within the back, and a head for the button hav-

ing a post thereon adapted to slidably enter 35 the aperture in the disk, and to be withdrawn therefrom only by unscrewing the same.

2. In a removable button, a flat disk having a central aperture with the body of the 40 disk slit adjacent the aperture to form spring tongues, a back for the button bent around the disk, and a cover disk for the back, said cover having rotatably mounted thereon a second disk, said second disk having 45 pointed tongues thereon, for the purpose described, said disks and back having apertures registering with the flat disk aperture, and a head for the button having a post thereon adapted to slidably enter the aperture 50 in the disk, and to be withdrawn therefrom only by unscrewing the same.

3. In a removable button, a back, a flat spring disk, a cover disk, and a revolvable 55 disk on the cover disk, said back bent around the three disks, said spring disk having its edges cut away to make it nonrotatable within the back, apertures through the assembly, and the spring disk having the portions 60 thereof adjacent the aperture split so as to form spring tongues, a head for the button, said head having a post adapted to slidably enter the aperture in the spring disk and to be withdrawn therefrom only by unscrewing.

EDWIN GEBHARDT.
